US00D869114S

(12) **United States Design Patent** (10) **Patent No.:** **US D869,114 S**
(45) **Date of Patent:** **** Dec. 3, 2019**

(54) **CART**

(71) Applicant: **Grow Solutions Tech LLC**, Vineyard, UT (US)

(72) Inventors: **Gary Bret Millar**, Highland, UT (US); **Mark Gerald Stott**, Eagle Mountain, UT (US); **Todd Garrett Tueller**, American Fork, UT (US); **Michael Stephen Hurst**, Farmington, UT (US); **Alan Ray Bentley**, Alpine, UT (US); **Taylor John Woodbury**, Provo, UT (US); **Shane York**, Morgan, UT (US)

(73) Assignee: **Grow Solutions Tech LLC**, Vineyard, UT (US)

(**) Term: **15 Years**

(21) Appl. No.: **29/638,296**

(22) Filed: **Feb. 26, 2018**

(51) LOC (12) Cl. **12-05**

(52) U.S. Cl.

USPC **D34/28**; D34/23

(58) **Field of Classification Search**

USPC D34/23, 28, 29, 34, 38; 248/346.02; 229/125.26, 122.28, 122.21, 120.11, 117, 229/113, 110; 108/57.28, 57.25, 57.1, 108/56.1, 55.3, 53.3, 53.1, 52.1, 51.3, 108/51.11

(57) **CLAIM**

The ornamental design for a cart, as shown and described.

DESCRIPTION

FIG. 1 is a top perspective view of a cart showing our new design;

FIG. 2 is a bottom perspective view thereof;

FIG. 3 is a top view thereof;

FIG. 4 is a bottom view thereof;

FIG. 5 is a front view thereof;

FIG. 6 is a rear view thereof;

FIG. 7 is a right side view thereof; and,

FIG. 8 is a left side view thereof.

The broken lines shown in the drawings are for the purposes of illustrating portions of the cart, which form no part of the claimed design.

1 Claim, 6 Drawing Sheets
